UNITED STATES PATENT OFFICE.

GERARDO TRAMUTOLO, OF NEWARK, NEW JERSEY.

BAGGAGE-TRANSFER.

1,273,424.

Specification of Letters Patent.

Patented July 23, 1918.

Application filed August 30, 1916. Serial No. 117,713.

To all whom it may concern:

Be it known that I, GERARDO TRAMUTOLO, a citizen of the United States, residing at Newark, in the county of Essex and State 5 of New Jersey, have invented certain new and useful Improvements in Baggage-Transfers, of which the following is a specification.

This invention relates to a mail, baggage, 10 etc., deliverer and receiver for railway trains.

The object of this invention is to provide a deliverer and receiver of the type above set forth that is wholly carried by the train 15 and is automatically operated as the car passes a platform adjacent the track.

Another object of this invention is to provide a device of the kind above described that is simple in construction, efficient in 20 operation and consists of the minimum number of parts.

With these and other objects in view, the invention consists of certain novel constructions, combinations and arrangements of 25 parts, as will be hereinafter fully described and claimed.

In the accompanying drawings:

Figure 1 is a fragmentary horizontal sectional view of a car provided with this device and the platform adjacent the car, the 30 same being shown in top plan.

Fig. 2 is an inverted plan view of the device as shown in Fig. 1.

Fig. 3 is a fragmentary transverse sectional view of the device as shown in Fig. 35 1, and

Fig. 4 is a detail perspective view of the improved device.

Referring to the parts by reference numerals, the car floor is designated by the 40 numeral 10 and has an opening 11 formed therein adjacent the door of the car. Journaled in this opening 11 is a standard 12 that extends above and below the floor bottom 10 and that portion below the bottom 10 is designated by the numeral 13, the same being polygonal in cross section. An opening 14 is formed in the standard 12 at an appreciable distance from the car floor 10 45 and an operating bar 15 is adapted to be inserted in this opening, as is clearly shown in the accompanying drawings, for manual manipulation of the device. A pair of object engaging arms 16 and 17 are secured 50 to the standard 12 and engage the upper face of the car bottom 10, as clearly shown in Fig. 3, the arms 16 and 17 are flared at the ends thereof as at 18 and 19.

To normally retain the standard 12 in a desired position and thus position the arms 60 16 and 17 for the obvious purpose, there is connected with the portion 13 of the standard 12, a coil spring 20. A lever 21 is pivoted as at 22 to the under face of the car bottom 10, the said lever having an outwardly curved portion 23 and a notch 24 is formed in the same adjacent the opposite end thereof from the formation of the curved portion 23. A coil spring 25 is attached to one end of the lever 21 as is shown 70 to an advantage in Fig. 2, and normally retains the said lever in engagement with the standard 12 or, more specifically, the polygonal portion 13 is positioned in the notch 24 to prevent the rotation of the 75 standard. As is clearly shown in Figs. 1 and 2, a portion of the curved end 23 of the lever 21 extends beyond the side of the car and is adapted to be engaged by the ordinary platform, designated by the numeral 26 80 that lies adjacent the track on which the car runs.

In operation, the standard 12 is rotated against the tension of the spring 20 so that the same is in a position as shown in Fig. 1, 85 that is, the arm 16 is wholly within the car and a portion of the arm 17 projects therefrom. A package to be discharged, for the sake of convenience, designated by the numeral 27, is positioned as is shown in Fig. 90 1, against the arm 16 and a package to be delivered to the car is placed on the platform adjacent the car track in the path of the arm 17 and the arm and standard are retained in this position by means of the 95 engagement of the polygonal portion 13 of the standard with the lever 21. As the car passes the platform 26, the rounded end 23 of the lever 21 will engage the edge of the platform and rock the lever upon its pivot 100 point and thus move the notch thereof from engagement with the polygonal portion 13 of the standard 12 and the spring 20 will 105 oscillate the standard and move the arms 16 and 17 so that the package 27 will be deposited on the platform 26 and the package 28 that was placed in the path of the arm 17 will be deposited in the car. To reset the device, the bar 15 can be placed in the opening 14 and the rod moved against tension 110 of the spring 20 and the lever 21 will obviously move, by means of the spring 25,

so as to engage the rod to the standard and prevent the rotation of the same.

It is obvious that minor changes may be made in the form and construction of this invention without departing from the material parts thereof. It is therefore not wished to confine the invention to the exact form herein shown and described, but it is wished to include all such as properly come within the scope claimed.

I claim—

A device of the kind described, a support, a standard journaled in said support, said standard having a polygonal portion at one

end thereof, a spring in engagement with 15 said polygonal portion for urging said standard in one position, a pivoted lever on said support having a notch formed therein to receive said polygonal portion of said standard for releasably securing said standard in the position against the tension of said spring.

In testimony whereof I affix my signature in presence of two witnesses.

GERRY TRAMUTOLO.
